UNITED STATES PATENT OFFICE

PERCY P. BOWEN, OF NORTH TONAWANDA, NEW YORK

HAMMER MILL BLADE

Application filed December 9, 1929. Serial No. 412,604.

This invention relates to that type of disintegrating machine or pulverizer known as a "hammer mill", and relates more especially to this machine when so constituted as to pulverize the material by cutting or slashing rather than by crushing the same. In particular the invention relates to the cutting knives or blades of such a hammer mill and to the means of obtaining the maximum cutting efficiency and operating economy therefrom.

The object of the invention is to provide a hammer mill blade which will cut or pulverize a large quantity of material per hour with a minimum power expenditure; with a low cost of maintenance and replacements; and with a minimum loss of time due to shutdowns.

In the accompanying drawings:

Figure 1 is a vertical transverse section through a typical hammer mill pulverizer showing a plurality of the improved hammer mill blades installed therein.

Figure 2 is an enlarged perspective of one of said blades.

Figure 3 is an enlarged perspective of a modified form of blade.

Figure 4 is an enlarged layout of the improved blade in relation to the power shaft 30 of the hammer mill, illustrating the geometric values of the cutting face of said blade.

Figure 5 is a considerably enlarged fragmentary side view of one of the hammer mill blades showing a modified form of cutting face which has a small, positive cutting angle.

Similar characters of reference indicate like parts in each of the several views.

Figure 1 illustrates a typical hammer mill pulverizer having a main frame 10 in which is suitably journaled a power shaft 11, the latter being adapted to be supplied with power from an external source in any suitable manner. Secured by a key 12 or otherwise to said power shaft are a plurality of flanges 13 which are disposed transversely to and project out from said power shaft and are preferably provided at their central portions with hubs 14 in the usual and well known manner.

Disposed parallel to and concentric with

the power shaft 11 is an annular row of pivot shafts 15 which are suitably secured to and are thereby rotated with aforesaid rotor flanges 13 and the power shaft 11. Pivots mounted upon said pivot shafts 15 are a plurality of hammer mill blades 16, which are thrown outwardly by centrifugal force into the position of Fig. 1 whenever they are rapidly rotated together with the power shaft 11 and rotor flanges 13.

The material to be pulverized or disintegrated is fed into the hopper 17 at the upper part of the machine and flows down upon a beater plate 18 arranged adjacent to the downward path of the blades where the material receives a rapid succession of violent slashes from the rapidly revolving blades 16. The slashed material is thence thrown or carried down upon a plurality of grid bars 20 which are suitably spaced from each other to

allow any certain desired size of pulverized material to fall or to be sucked through the spaces between said grid bars and to be received within the pulverized-material pit 21, which is arranged below the grid bars and, in usual practice, is subject to a vacuum action

to ensure the rapid movement of pulverized material through said grid bars 20. Any material too coarse to pass through between said grid bars and not cut into sufficiently fine pieces while lying thereon, is thrown up and around with the blades 16 and again falls upon the beater plate 18 and again slashed and from thence again thrown upon the aforesaid grid bars 20.

The present invention resides in the blades 16, which are preferably punched or stamped from sheet metal into the form shown in Fig. 2, the opposite ends, faces and edges of the same being preferably symmetrical about their longitudinal, transverse and perpendicular axes, for reasons which will appear later.

On what we may, for convenience, call the inner end of the blade is formed a pivot hole 22^a which is adapted to embrace a companion pivot shaft 15 so as to be pivotally connected therewith. Assuming now a counter clockwise rotation as in Fig. 1, it is evident that the cutting action of the blade will occur at the lower right hand corner of the blade as shown

in Figs. 2 to 5 inclusive, i. e. at the outer portion of the advancing side of the blade which outer portion thereby acts as a cutting face 23^a. It is here assumed that the material being handled is capable of being slashed and not merely and solely pulverized by impact the latter condition not being within the purview of the present invention.

To ensure proper cutting action, it is very desirable that this cutting face 23^a have the proper "top" rake, i. e. that said cutting face be disposed at a proper angle relative to a radius 24 passing from the axis of the power shaft 11 out to the outer corner 25^a of the blade. The proper selection of the angle for the said cutting face is properly a function of this radius 24, but this angle may also be defined as relative to the axis or the parallel sides of the blade. For some classes of material, maximum cutting efficiency is obtained with the form of blade 28 (shown in Fig. 5) by the use of a very slight positive rake, i. e. of a cutting face 125 having a "top" rake which is positive (or mathematically plus) relative to said radius 24. In other words the "top" rake or cutting face angle of the blade shown in Fig. 5, (which, of course, passes through the outer end 125^a of said cutting face) is so disposed as to make a slight angle in a clockwise direction from the radius 24 aforementioned, about the said outer corner 125^a as a center of rotation. If the said cutting face were to lie in a plane coincident with the outer, parallel edges of the blade, the value of the cutting face angle (see Fig. 4) would be positive and equal to the angle whose sine is one-half the width of the blade divided by the length of the radius 24 from its origin at the axis of the power shaft 11 out to the outer corner 25^a of the active cutting face 23^a. It is, however, the object of this invention to not have so great a positive rake as this, but, instead, to have either a smaller positive rake as in Fig. 5 or a small negative rake as in Fig. 4, the latter being preferable when pulverizing most classes of material.

Thus in most uses of the hammer mill it is preferable to have the cutting face 23^a make a small negative angle with the radius 24, as shown particularly in Fig. 4; i. e., a maximum of cutting efficiency is obtained by having the cutting face angle (which passes through the outer corner 25^a of the blade) make a small counter clockwise angle with said radius 24 and with said outer corner 25^a as a theoretical center. This ensures that all material cut up by the extreme corner 25^a of the blade is caused to be pushed inwardly toward the axis of the power shaft 11 and thus away from the said corner 25^a so that the latter is caused, in effect, to be self-clearing and always in condition to take fresh new bites on a succession of pieces of material.

In the course of time, however, the cutting face 23^a of each hammer mill blade will be-

come dull, and this invention contemplates the successive resharpening of said cutting face until said face recedes to a final cutting face which is defined by the indicating line 24^a, all of said resharpenings being obviously rendered possible without taking any of the cutting blades out of the hammer mill.

The said indicating line 24^a which defines said final cutting face may be physically marked on the surface of the blade in any suitable manner, preferably by a slight groove or a fin formed upon one or both faces of the blade by suitably forming the dies which perform the punching or stamping operation. For purposes of illustration, the width and depth of the indicating line has been very considerably exaggerated in the drawings, only a very faint line or fin being required in practice. Said indicating line may, if desired, be formed by etching, filing, prick punch marking or otherwise.

When the said final cutting face at 24^a of any one blade becomes excessively dull, it is obvious that usually all of the final cutting faces of all the other blades 16 have become dull too, in which case all of the pivot shafts 15 may be pulled out through their holes in the rotor flanges 13, thereby disengaging or "threading off" all of said blades from their companion pivot shafts 15. Thereupon, the pivot hole 22^a may again be employed to pivotally connect each blade with its companion pivot shaft 15, but in this case, with each blade turned backwards from its initial position, that is with the other longitudinal edge positioned "forwardly", so that the cutting face 230^a now becomes the active cutting face. This face is in turn ground back successively as each previously ground cutting face becomes dulled through use, until the grinding recedes to the indicating line 240^a.

When this "secondary" final cutting face 230^a, now ground back to indicating line 240^a, becomes too dull, the whole blade is again removed from its companion pivot shaft 15 and each blade turned end for end so that the pivot hole 22^b acts as the pivot for each blade upon its companion pivot shaft. In practice all of the blades are usually simultaneously thus turned end for end in this manner. It is obvious that this change has furnished another pair of cutting faces 23^b and 230^b which are adapted to be successively ground back in the same manner as cutting faces 23^a and 230^a. To state the matter more broadly, the blade is so formed as to be symmetrical about all three of its axes, so that either end may be disposed outwardly and, in each of the latter two positions, either of the two edges may be disposed forwardly, so that the effect is that each blade has four cutting faces, with two faces at each end of each of its side edges.

It will be noticed that the opposite ends 26^a and 26^b of each blade are symmetrically curved, the radius of said curved ends being

approximately the distance out from the axis of the power shaft 11 when the blade is in normal operating position, as in Fig. 1. By this means the clearance between all the four outer corners 25^a, 250^a, 25^b and 250^b of the cutting faces, as said faces are successively ground back, are equidistant from the axis of the power shaft 11 and thereby maintain an equal clearance away from the grid bars 20 and beater plate 18 when the blade is in normal cutting position. This clearance is slightly reduced as the blade swings about its pivot shaft 15, if the curve has, as already mentioned, a radius equal to that from the axis of the power shaft 11. This is not usually objectionable, but, if it is desired to maintain a very small minimum clearance at the center of the blade, this radius may be reduced somewhat, in which case the clearance will not remain precisely uniform (in the normal position of the blade) as the cutting face is ground back, but the minimum clearance will (as in this case desired) be smaller. This state of affairs does not exist if the blades are pivoted directly upon the power shaft, as is obvious, and it is within the purview of the present invention that the blades be so mounted for the grinding of special classes of material.

30 A modified form of blade 27 is shown in Fig. 3 in which additional cutting faces 28^a, 280^a, 28^b and 280^b are added at the central portions of the ends of the blade. This modified blade is more particularly adapted for pulverizing very light flocculent material.

In general, the novel form of hammer mill blade constituting the present invention is of considerable commercial value in that provision is made for successively sharpening the cutting faces and with these successive operations conveniently performable without dismantling any part of the hammer mill, as is now customary practice. Furthermore, with the usual construction of the present invention, this successive grinding back of the cutting face does not alter the clearance between the outer ends of said cutting faces and the grid bars of the hammer mill. In addition to this, provision is made for most advantageously using all four corners of each blade so as to enable each to serve in succession as a cutting face, thereby considerably extending the life of each blade and increasing the economy of operation. Furthermore suitable provision is made for clearly indicating the maximum amount of grinding to be allowed so that the re-grinding operation may be placed in the hands of unskilled workmen. Besides this, the blade is of such form as to be readily produced by a single punching or stamping operation.

I claim as my invention:

65 A blade for hammer mills having a body of sheet metal provided adjacent to its op-

posite ends with pivot openings either of which is adapted to pivotally mount said body on a rotary support, and opposite ends of said body being curved continuously and concentrically with the axis of said rotary support when either end of the body is in the operative position, said body having opposite parallel longitudinal edges and inclined faces at its four corners any one of which may be brought into the operative position and each of which recedes at an angle from one corner of the body and is arranged inwardly from the respective longitudinal edge of the blade body.

In testimony whereof I hereby affix my signature.

PERCY P. BOWEN.
